(57) **CLAIM**

The ornamental design for a housing for a communication device, as shown and described.

DESCRIPTION

FIG. 1 is a perspective view of a housing for a communication device showing our new design.

FIG. 2 is a front view thereof.

FIG. 3 is a rear view thereof.

FIG. 4 is a first side view thereof.

FIG. 5 is a second side view thereof.

FIG. 6 is a top view thereof; and,

FIG. 7 is a bottom view thereof.

The broken line showing of environmental structures is for illustrative purposes only and forms no part of the claimed design.
